AIRPLANE

Vincent J. Burnelli, New York, N. Y., assignor, by mesne assignments, to Burnelli Aircraft, Ltd., Dover, Del., a corporation of Delaware

Original No. 1,799,777, dated April 7, 1931, Serial No. 234,320, November 19, 1927. Application for reissue March 31, 1933. Serial No. 663,819

6 Claims. (Cl. 244—31)

This invention relates to airplanes and my improvements are directed to certain novel structural features involving the fuselage with respect to its means of supporting connection 5 with the power plant, the airplane wings and the tail group.

Thus one object of my invention is to provide lateral, forwardly projecting extensions of the fuselage which are adapted to support engines 10 mounted thereby at opposite sides of the fuselage nose. It is by these means that two engines carried by a fuselage at opposite sides of the centre of resistance through the airplane may operate respective propellers, in advance of the 15 fuselage nose, in the same vertical plane in instances where the normal width of the fuselage would not permit sufficient spacing between propeller centres if the engines were contained within the fuselage.

20 Another object of my invention is to secure the opposite monoplane wings to the upper sides of the fuselage, giving said wings each a shoulder effect where they are rooted to the fuselage to thus leave exposed the side walls of the fuselage 25 so that windows in said walls will be available to passengers in the fuselage for observation purposes, without resorting to wing distortion.

Still another object of my invention is to provide a relatively narrow, hollow rearward extension 30 from the fuselage to serve as a support for the empennage or tail group and the tail skid, this feature being particularly desirable when the fuselage is of considerable width and is not itself extended in length to tail group.

35 Other features and advantages of my invention will hereinafter appear.

In the drawing:

Figure 1 is a side elevation of an airplane containing the several features of my invention. 40 Fig. 2 is a top plan view thereof, the wings being broken away.

Fig. 3 is a partial front elevation of the same, and

Fig. 4 is a section on the line 4—4 of Fig. 2. 45 In said figures let 1 indicate an airplane fuselage and 2, 2, a pair of monoplane wings extended therefrom.

Attached to the opposite sides of the fuselage and extending forwardly thereof are the structures 3, 3 which each constitute a support for 50 an engine. In the example of the drawing the engines 4, 4 are shown as of the radial, air cooled type, but obviously other types of engines may equally well be mounted upon or contained within 55 in the structures 3, 3, whose main purpose is to

support the engines at the sides of the fuselage with the propellers projecting forwardly of the fuselage nose.

The disposition of the propellers 5, 5 which are operated by the engines 4, 4 is such that they 60 may rotate clearly in the same vertical plane. Rooted to and extending upwardly from the top sides of the fuselage are the wing shoulders 6, 6 and it is from these shoulders that the wings 2, 2 are spanned outwardly, said wings thus lying 65 in an approximately horizontal plane that is elevated above the fuselage top to thereby expose windows 7 in the fuselage sides, whereby the said windows may be disposed at suitable height from the fuselage floor, permitting passengers 70 seated in the fuselage to have full and unobstructed view through the windows.

When the fuselage is of considerable width and does not extend rearwardly to itself serve as the support for the empennage and tail skid. 75 I provide a hollow, bulk-headed extension 8, suitably connected to the fuselage and of relatively narrow width, substantially as shown, the length of said extension enabling it to support the empennage 9 and also to carry the tail skid 10. 80

It will be noted that the upward projection of the wing roots above the fuselage top defines a channel or concaved effect between said wing roots and fuselage top that tends to diminish head resistance. 85

This application is a continuation in part of my application Serial No. 435,481 filed January 6, 1921.

Variations within the spirit and scope of my invention are equally comprehended by the foregoing disclosure: 9

I claim:

1. The combination with an airplane-fuselage of a pair of engine mountings attached respectively to opposite outer side walls of said fuselage, and projecting forwardly thereof, said mountings constituting a part of the fuselage structure.

2. The combination with an airplane having monoplane wings and a fuselage of a pair of engine mountings attached respectively to opposite outer side walls of said fuselage and projecting forwardly thereof, said mountings constituting a part of the fuselage structure, and engines carried by said mountings.

3. The combination with an airplane having a fuselage and wings of a pair of nacelle engine mountings lying against the fuselage, respectively at opposite outer sides thereof, projecting

forwardly of said fuselage and directly connected thereto in front of the wings.

4. The combination with an airplane having a fuselage and wings of a pair of nacelle engine 5 mountings lying against the fuselage, respectively at opposite outer sides thereof, projecting forwardly of said fuselage and directly connected thereto independently of the wings.

5. The combination with an airplane having 10 a fuselage and wings of a pair of nacelle engine mountings lying against the fuselage respectively at opposite outer sides thereof, projecting forwardly of said fuselage and directly connected thereto in front of the wings, engines carried

by said mountings, and propellers that are caused to operate by said engines in advance of the fuselage nose.

6. The combination with an airplane having a fuselage and wings of a pair of nacelle engine 80 mountings lying against the fuselage respectively at opposite outer sides thereof, projecting forwardly of said fuselage and directly connected thereto independently of the wings, engines carried by said mountings, and propellers that are 85 caused to operate by said engines in advance of the fuselage nose.

VINCENT J. BURNELLI.
